UNITED STATES PATENT OFFICE.

EUGENE TOMLINSON, OF KANSAS CITY, KANSAS.

RADIATOR FILLING AND COOLING CAP.

Application filed June 5, 1922. Serial No. 565,825.

To all whom it may concern:

Be it known that I, EUGENE TOMLINSON, a citizen of the United States, and resident of Kansas City, county of Wyandotte, and State of Kansas, have invented a certain new and useful Improvement in Radiator Filling and Cooling Caps, of which the following is a complete specification.

This invention relates to combined radiator filling and cooling caps for use with automobile radiators and has for one of its objects to produce a device which is readily adjustable for the filling of the radiator, without the necessity of removing the radiator cap.

Another object is to produce a device of the character set forth which will maintain a current of air within the radiator for condensing any steam which may be formed and thereby maintain the water supply substantially constant.

A further object is to produce a device of the character described, which is ornamental in appearance and is of simple, strong, durable, efficient and inexpensive construction; and in order that it may be fully understood, reference is to be had to the accompanying drawing, in which:

Figure 1 is a front view of the device attached to a radiator filling neck.

Figure 2 is a central vertical section through the same, and illustrates in dotted lines the position the device will occupy when used in filling the radiator.

Figure 3 is a section on the line III—III of Figure 2.

Figure 4 is a section on the line IV—IV of Figure 2.

Figure 5 is a central vertical section through a modified form of one part of the invention.

In the said drawing, where like reference characters identify corresponding parts in all of the figures, 1 illustrates an automobile radiator, 2 the filling neck thereof, and 3 the upper end of the customary overflow pipe which ordinarily projects some distance within the neck and above the normal water level.

50 The filling neck, as illustrated, is externally threaded at its upper end and engaged with said threads is a tubular extension 4 formed with an abutment portion 5 adapted to come into contact with the upper extremity of the filling neck. The device projects somewhat upward above the end of

the filling neck and is formed with a second abutment portion 6 and terminates in an externally threaded reduced portion 7.

Secured within the extension 4 and preferably a slight distance above the horizontal plane of the top of the filling neck is a cone deflector 8 located with its point in the vertical axis of the filling opening, and around the base of said cone, a series of openings 9 are formed, for a purpose which will hereinafter appear.

Adapted to be secured to the upper end of the extension 4 is the lower end of a funnel member 10 equipped with a marginal flange 11 at its lower end for resting on the extremity of the part 7, and said funnel is secured in position by means of a threaded collar 12 in engagement with the external threads of the member 7 and formed with a lip 13 adapted to clamp down upon the lip 11 of the member 10 and retain same firmly on its seat, as will be readily understood.

The funnel member 10 is curved at its upper end and is formed with a marginal flange 14, to which is freely secured for rotation, the mouth of the funnel 15, formed at its lower end with a bead 16 receiving the flange 14 of the lower funnel member 10. In this connection it is desirable to point out that the connection between members 10 and 15 possesses sufficient frictional resistance as to prevent accidental turning movement of the member 15. It will be evident from the construction just described, that the mouth member 15 may be rotated to occupy the dotted line position (Figure 2), when it is desired to fill the radiator.

Preferably formed integrally with the passageway of the funnel member 10 is an inverted truncated cone deflector 17, it being evident that a pocket 17^a will be formed below said truncated cone and above the cone deflector 8.

The construction shown in Figure 5 illustrates a slightly modified form, in which the extension 4 is formed integrally with the inverted truncated cone 17 in addition to the deflector 8.

The operation of the device is as follows:—Normally the mouth of the funnel will be turned forwardly in order to catch the current of air set up by the vehicle in its course of travel. The air will enter the funnel and pass down through the truncated cone and will strike and be divided by the

deflector 8 and will pass down through the openings 9 into the top of the radiator, and will exit through the overflow pipe 3.

If the water in the radiator becomes excessively hot, and steam is generated, the steam will, of course, attempt to pass upwardly through the openings 9 and through the opening in the member 17, but the cool current of air passing downward through the funnel will chill the parts and cause a condensation of steam after which the water will drain back into the radiator through the openings 9.

In order to add to the attractive and ornamental appearance of the device, a ring 18 equipped with a pair of side wings 19, or the like, is slipped on the extension 4 and rests on the abutment 5 (see Figure 2), the threaded portion of the collar 12 being received inside the upper edge of the ring. The ring 18 is turned to the desired position and then fastened securely in such position by means of a set screw 20, as will be readily understood.

When it is desired to fill the radiator, the mouth of the funnel is rotated to occupy the position shown in dotted lines (Figure 2), and after the filling operation, it is again rotated to face in a forward direction to receive the current of air set up by the passage of the car, as above pointed out, it being evident that the frictional connec-

tion between the funnel members, above-mentioned, will hold the mouth member of the funnel turned in any desired position of adjustment.

From the above description, it will be apparent that I have produced a device of the character described, which possesses all of the features of advantage pointed out as desirable; and while I have described and claimed, the preferred embodiment of the same, I reserve the right to make all changes properly falling within the spirit and scope of the appended claim.

I claim:—

The combination with an automobile radiator nipple, of an extension threaded thereon and of reduced diameter and threaded at its upper end, a downwardly opening funnel in the upper end of said extension, a conical deflector in the lower end of said extension and alined with the full opening and formed with a series of perforations surrounding its base, a filling member resting on the upper end of the extension, and a collar securing said filling member in position and having threaded engagement with the upper end of said extension.

In witness whereof I hereunto affix my signature.

EUGENE TOMLINSON.
